United States Patent Office

Des. 192,850
Patented May 22, 1962

192,850

LIVESTOCK FEEDER

Frank C. Bishop, P.O. Box 308, Monterey, Calif.

Filed Dec. 1, 1961, Ser. No. 67,759

Term of patent 14 years

(Cl. D12—2)

FIG. 1.

FIG. 4.

FIG. 2.

FIG. 3.

FIG. 1 is a top plan view of a livestock feeder showing my new design;

FIG. 2 is a view in front elevation of the same;

FIG. 3 is a view in side elevation of the same;

FIG. 4 is a view in perspective of the same.

The undisclosed side is substantially the same in appearance as the side shown, and the rear is substantially like the front.

I claim:

The ornamental design for a livestock feeder, substantially as shown and described.
